UNITED STATES PATENT OFFICE.

JAMES W. MALLONEE, OF BENEDICT, NEBRASKA.

PUMP-PISTON.

No. 855,647.

Specification of Letters Patent.

Patented June 4, 1907.

Application filed April 25, 1906. Serial No. 313,643.

To all whom it may concern:

Be it known that I, JAMES W. MALLONEE, a citizen of the United States, residing at Benedict, in the county of York and State of Nebraska, have invented certain new and useful Improvements in Pump-Pistons; and I do hereby declare the following to be a full, clear, and exact description of the invention, such as will enable others skilled in the art to which it appertains to make and use the same.

My invention relates to new and useful improvements in pump pistons and more particularly to that class adapted to be used in connection with force pumps.

My object is to provide a construction adapted to be used for pumping water or air.

A further object is to provide a piston that can be reversed and thereby force air or water in either direction.

Other objects and advantages will be hereinafter referred to in the specification and pointed out in the claims.

Referring to the drawings, which are made a part of this application—Figure 1 is a perspective view showing the casing surrounding the piston, partly broken away, and, Fig. 2 is a longitudinal central section through the casing and piston.

In the drawings similar reference numerals indicate corresponding parts throughout, in which

1 designates my improved piston to which is attached a suitable operating rod 2, said rod having a reduced portion 3, which is adapted to take into a suitable threaded opening 4 in the piston 1. The reduced portion 3 is of sufficient length to pass entirely through the piston 1 so that the piston will fit upon said reduced portion from either side. A channel 5 is cut into one side of the piston 1 in which is adapted to be seated a check valve 6, said check being held in position in the channel 5 by means of a washer 7, said washer being interiorly threaded to take on to the threaded end 8 of the piston 1. A series of openings 9 are disposed through the piston 1 and intersect the channel 5 and are so located that when the piston 1 is being moved in one direction the check valve 6 will cover all of said openings and stop passage of air or water therethrough. A packing ring 10 is entered into a channel 11 in the periphery of the piston 1, said packing ring having its meeting ends split and

adapted to overlap as indicated at 12 in Fig. 1.

That end of the piston opposite the channel 5 is provided with a leather ring 13, said ring being so disposed that the free ends 60 thereof will engage the side walls of the piston chamber 14 and retard the passage of water around the periphery of the piston 1. The ring 13 is secured to the piston 1 in any preferred manner as by directing screws 13^a 65 through the ring and into threaded sockets in the piston. The chamber 14 as shown in the drawings is adapted to be used when the piston 1 is compressing air, one end of said chamber being provided with a series of openings 15 through which the air is adapted to pass into the interior of said chamber 14 and to the opposite end of said chamber is secured a check valve 16 of the usual or any preferred form.

In operation when the piston 1 is drawn to the end of the chamber having the openings 15 the check valve 6 is moved away from the openings 9 and air forced through said openings into the end of the chamber adjacent 80 the valve 16 and on the return stroke of the piston 1 the check valve 6 is clamped tightly by pressure over the openings 9 and so held until said piston has completed its stroke in the opposite direction, thereby forcing the 85 air through the check valve 16 into a suitable reservoir (not shown), and it will be clearly understood that when the piston is traveling toward the end having the check valve 16 the suction caused thereby will draw additional air through the openings 15, thus accumulating a supply of air to be forced through the openings 9 on the opposite stroke of said piston. If it is desired, however, to pump air from any particular place 90 and discharge it into the open atmosphere the piston 1 may be reversed on the reduced end 3 of the rod 2 when the reverse operation will take place from that previously described.

When the device is adapted to be used for pumping water the series of openings 15 in the chamber 14 are dispensed with or closed in some suitable manner and the chamber provided with a suitable connection 17 having a check valve 18 thereon, said connection being disposed in coöperation with a supply of water, the operation of the piston 1 being the same as that disclosed when the device is used for pumping air. The quantity of 100 105 110

air or water passing through the openings 9 may be readily regulated by turning the washer 7 upon the threaded end 8 of the piston 1 so that the check valve 6 can be placed 5 in closer relation to or farther away from that end of the openings 9 communicating with the channel 5, thereby allowing a greater or less amount of air or water to pass there-through. When the piston 1 is used for 10 pumping air it is necessary to use a lubricant to cause the same to slide freely in the chamber 14 and to this end I have provided a suitable inlet 19 through which oil can be introduced into the chamber 14.

15 What I claim is—

1. In a device of the class described the combination with a suitable chamber; of a piston slidably mounted in said chamber, a rod secured to said piston, said piston having 20 a channel at one end, a check valve disposed in said channel, said piston also having a plurality of longitudinal openings therethrough adapted to be closed by said check valve, a washer secured to the threaded portion of 25 said piston adapted to retain said check valve in position and adjust the same relative to said openings.
2. A device of the class described compris-

ing a cylinder, a piston slidably mounted in said cylinder, a rod having a reduced end 30 upon which said piston is adapted to take, a packing ring disposed in a channel around said piston, a packing leather secured to and surrounding one end of said piston, said piston having a channel in one end thereof and a plurality of openings through said piston, a check valve disposed in said channel and adapted to close said openings on one stroke of the piston and a washer adapted to adjustably secure said check valve in said 35 channel.

3. In a device of the class described a piston having a channel at one end thereof, and a plurality of longitudinal openings through said piston and registering with the channel, 40 a check valve movably disposed in said channel and a washer adapted to adjustably secure said check valve in said channel.

In testimony whereof I have signed my name to this specification in the presence of 45 two subscribing witnesses.

JAMES W. MALLONEE.
